UNITED STATES PATENT OFFICE.

FRANK KUHN, OF DETROIT, MICHIGAN.

ELECTRICAL HEATING UNIT.

1,107,320.

Specification of Letters Patent. Patented Aug. 18, 1914.

Application filed September 8, 1913. Serial No. 788,711.

To all whom it may concern:

Be it known that I, FRANK KUHN, a citizen of the United States of America, residing at Detroit, in the county of Wayne and State of Michigan, have invented certain new and useful Improvements in Electrical Heating Units, of which the following is a specification, reference being had therein to the accompanying drawings.

10 The invention relates to electrical heating units of the armored type, and it is the object of the invention to obtain a simplified and improved construction as hereinafter set forth.

15 In the drawings: Figure 1 is a plan view of the unit; Fig. 2 is an enlarged cross section thereof; Fig. 3 is a central longitudinal section showing one of the intermediate stays for the armor; and Fig. 4 is a diagram

20 showing the manner of assembling the parts.

My improved construction is particularly applicable for use in forming air heaters and similar devices in which different heating effects may be produced by variable 25 groups of standard units. To simplify the operation of assembling the units they are armored, and the present invention is designed to facilitate the armoring of the unit.

A is the insulated resistor unit, the specific construction of which forms no part of 30 the present invention, and which therefore is not shown in detail.

B is an armor plate which is formed at its opposite edges with the upwardly and outwardly bent flanges C and D. The space 35 between the flanges C on the opposite sides is suitable to receive the unit A and to hold the same from displacement.

E is a second armor plate, which also is 40 provided with upwardly and outwardly bent flanges F and G, the flange G being relatively longer than the flange D on the member B, while the flange F is shorter than the flange C. As a result there will be provided 45 sufficient space between the plates B and E for the reception of the unit A when engaged under pressure. To secure the parts together the flange G is then turned over the flange D, as shown at H.

50 With the construction as described, when the flanges D and G are seamed together the two plates B and E will be pressed into firm contact with the insulated resistor so as to produce good heat conduction therebetween. 55 A still better contact is obtained by provid-

ing one of the plates, such as E, with a series of tongues I struck up from the sheet metal, and which pass through apertures in the insulator and registering apertures in the opposite armor plate and are then clenched, as 60 indicated at J. These intermediate stays will greatly assist in holding the plates together, and as they are formed by the tongues of sheet metal they are of small cross section and may be easily arranged between convolutions of the resistor out of contact therewith. The forming of the flanges F, G and C, D as shown, with substantially rectangular bends, is also advantageous, as it provides edge abutments for the insulator 70 which will hold it from displacement. The terminals of the resistor may be connected to suitable terminal contacts at the ends of the armor, such as shown at K.

What I claim as my invention is:

1. In an electrical heating unit, the combination of opposite armor plates, an insulated unit clamped therebetween, and a stay between said plates formed by a tongue struck out from one of the plates extending 80 through said insulating unit and passing through a slit in the opposite plate and clenched.

2. An electrical heating unit, comprising an armor plate having rectangularly-bent 85 upward and outward flanges at its opposite edges, an insulated resistor extending between said flanges and in contact with said plate, and a second armor plate provided with similar flanges telescopically engaging 90 said first plate and having its outwardly-extending flanges seamed together.

3. An electrical heating unit, comprising an armor plate having upwardly and outwardly bent flanges at the opposite edges 95 thereof, an insulated resistor arranged between said flanges in contact with said plate, a second armor plate having similar flanges telescopically engaging the first plate, said outward flanges being seamed together, and 100 a tongue struck up from one of said plates passing through a slit in the opposite plate and clenched.

4. An electrical heating unit, comprising a flat armor plate having rectangularly-bent 105 flanges at its opposite edges terminating in rectangularly-bent outwardly-extending portions, an insulated flat resistor element extending between the first-mentioned flanges and lying adjacent to said plate, and a sec- 110

ond armor plate having flanges similar to those of the first plate and telescopically engaging the latter, the outwardly-extending flanges of the two plates being seamed together to exert a clamping tension upon the said plates and the interposed insulated resistor.

In testimony whereof I affix my signature in presence of two witnesses.

FRANK KUHN.
